(No Model.)

C. SEE.
HORSE HITCHING DEVICE.

No. 448,270.

Patented Mar. 17, 1891.

Inventor:-

Christian See,

Attorneys.

UNITED STATES PATENT OFFICE.

CHRISTIAN SEE, OF ST. PAUL, MINNESOTA.

HORSE-HITCHING DEVICE.

SPECIFICATION forming part of Letters Patent No. 448,270, dated March 17, 1891.

Application filed November 8, 1890. Serial No. 370,725. (No model.)

To all whom it may concern:

Be it known that I, CHRISTIAN SEE, of St. Paul, Ramsey county, Minnesota, have invented certain Improvements in Horse-Hitching Devices, of which the following is a specification.

My invention relates to improvements in attachments to wagons; and it consists in improved means for raising and lowering the check or hitch weight attached to the team.

My invention further consists in the construction and combination hereinafter described, and particularly pointed out in the claims.

15 In the accompanying drawings, forming part of this specification, Figure 1 is a side elevation of a wagon of the type described fitted with my improvement. Fig. 2 is a partial sectional plan view of the rear end of the same. Fig. 3 is a rear elevation of the same. Fig. 4 is a detail of the clutch mechanism engaging the lifting-strap of the hitching-weight. Figs. 5 and 6 are details of the hooks attached to the wheel-spokes for automatically lifting the hitching-weight, and Figs. 7 and 8 are details of the lifting strap-holder by means of which it is brought into position to be engaged by a hook upon the adjacent wheel-spoke to raise the hitching-weight.

30 In the drawings, 2 represents the body or platform of the wagon.

3 is an open wire guard surrounding the wagon-platform, and 4 is a shelf or receptacle underneath the wagon-body.

35 The front wheels 5 are shown low to pass underneath the body for convenience in turning.

8 is the driver's seat mounted upon the standard 7, secured at the rear of the wagon 40 upon the step or platform 6 beneath a semi-circular space or recess in the rear of the wagon.

9 are cushions or knee-pads upon each side of the recess to protect the limbs of the driver.

45 Arranged near the center of the wagon-platform is the standard 10, having at its top rein loops or rings 11, through which the harness-reins 12 are passed and supported above the contents of the wagon and convenient to the hand of the driver. A hitch-weight strap 13 may also be carried through one of the rings of the support and secured at one end

to the bridle-bit of the team, the other end being carried downward through the body or platform to the weight 14 beneath. In order 55 to lift the weight from the ground when it is desired to start the team, I prefer to provide a lifting-strap 15, attached to the weight and carried over a drum or roller 16, supported in suitable bearings underneath the wagon-body, 60 and thence over another roll 17 underneath and at one side of the wagon-body adjacent to one of the hind wheels 18, the end of the strap being provided with a ring 19, standing in a vertical position. In order to hold it in 65 this position, I pass the strap between the rolls 20 of the strap-holder 21, which is fitted with a rod or handle 22, supported lengthwise of and underneath the body, and having a handle 23, by means of which it can be pulled 70 backward, a spring 24 upon the rod tending to hold it in its forward position. Upon the spokes of the adjacent wheel 18 I arrange hooks or projections 25 in such position that they successively pass close to the strap- 75 holder 21 and will engage the ring of the strap when the holder is drawn back by means of its handle, but will pass by the ring when the holder is in its forward position. It will thus be seen that if the strap-holder is drawn 80 back the first spoke-hook which passes by with the forward movement of the wagon will engage the ring of the strap and pull it downward, thus lifting the weight by means of the strap until the wheel in its rotation turns the 85 hook in such a position as to allow the ring to slip off. In order to hold the weight in its raised position, I prefer to arrange in connection with the roll 16 a cam-shaped clutch 26, which bears upon the strap and presses it 90 against the roll. A weight 27 upon an arm 28, connected to the cam, serves to hold the cam in bearing contact with the strap at all times, thus allowing the strap to be drawn through it to raise the weight, but preventing 95 it from slipping in the opposite direction. A strap 29, attached to the clutch-weight and passing over suitable supports connected to the wagon-body to the recess at the rear, and fitted preferably with a handle 30, is employed 100 to lift it and release the strap, so as to drop the hitching-weight. I do not confine myself to this particular construction, as other means may be employed for bringing the lifting-

strap into engagement with the wagon-wheel, so as to lift the weight when desired.

31 is a curved pivoted brake-lever having the arm or treadle 32 and provided with a ratchet 34 and pawl 33 for holding the brake set and a handle 35 for releasing the brake. The short arm of the brake-lever is connected to the bell-crank lever 37, which has pivotal support underneath the wagon-body, the other 10 arm being connected by means of a link 38 to a crank of the brake-shaft 39. A spring 40, connected to the depending arm of the bell-crank lever, tends to hold the brake 41 thrust forward and off the wheel 18. It will thus 15 be seen that the driver from his seat at the hind end of the wagon has complete control of the team and vehicle, having the reins supported in easy reach and means at hand for operating the brakes and for raising and lowering the hitching-weight without moving 20 from his seat.

I claim—

1. In a horse-hitching device, the combination, with a wagon having a rein support or 25 standard, of a strap passed through the said standard connecting the bridle-bit and the hitching-weight, a lifting-strap for said weight, a spring-controlled sliding strap-holder operated by the driver, and a device 30 upon said strap adapted to be engaged by the wagon-wheel when brought into proximity to it by the sliding of said holder, substantially as and for the purposes set forth.

2. In a horse-hitching device, the combination, with the wagon, the hitching-weight, and 35 its lifting-strap, of a movable support for said strap operated by the driver and devices

upon one of the wagon-wheels engaging said strap and pulling upon the same to lift said weight, substantially as and for the purposes 40 set forth.

3. In a horse-hitching device, the combination, with the wagon, the hitching-weight, and its lifting-strap, of supports for said strap upon the wagon-body, a sliding strap-holder, 45 means operated by the driver for shifting the position of said holder, and devices upon said wheel engaging said strap when brought into proximity to them, substantially as described.

4. In a horse-hitching device, the combination, with the wagon, the hitching-weight, and its lifting-strap, of a strap-supporting drum journaled underneath the wagon-body, a clutch for said strap, means operated by the driver for releasing said clutch, a movable 55 support for the strap adjacent to one of the wagon-wheels and operated by the driver, and devices upon the wagon-wheel for engaging said strap when brought into suitable position, substantially as described. 60

5. In a horse-hitching device, the combination, with the wagon, the hitching-weight, and the lifting-strap, of a clutch for said strap, means operated by the driver for bringing the strap into proximity with one of the 65 wagon-wheels, and projections upon the wagon-wheels for engaging said strap, substantially as and for the purposes set forth.

In testimony whereof I have hereunto set my hand this 4th day of November, 1890.

CHRISTIAN SEE.

In presence of—

T. D. MERWIN,
A. MAE WELCH.
